UNITED STATES PATENT OFFICE.

DANA G. HADLEY, OF WEST NEWBURY, MASSACHUSETTS.

INVALID'S CHAIR.

1,216,987.

Specification of Letters Patent. Patented Feb. 20, 1917.

Application filed March 5, 1915. Serial No. 12,351.

To all whom it may concern:

Be it known that I, DANA G. HADLEY, a citizen of the United States, residing at West Newbury, in the county of Essex and State 5 of Massachusetts, have invented certain new and useful Improvements in Invalids' Chairs; and I do hereby declare the following to be a full, clear, and exact description of the invention, such as will enable others 10 skilled in the art to which it appertains to make and use the same.

This invention relates to chairs and more particularly to a chair for invalids or for persons incapable of walking.

15 The primary object of this invention is the provision of a chair as specified which is convertible into a wheeled chair or rocker at the will of the person sitting therein, and also a chair where the angle of the back rest 20 of the chair may be varied for the comfort of the person.

With the foregoing and other objects in view this invention consists in such novel features of construction, combination and arrangement of parts as will be hereinafter more fully described, illustrated in the accompanying drawings and claimed.

25 In describing the invention in detail reference will be had to the accompanying drawings wherein like characters of reference designate like or corresponding parts throughout the several views, and in which:—

30 Figure 1 is a detail side elevation of the lower portion of the chair, showing the same positioned for use as a wheel chair,

Fig. 2 is a rear elevation of Fig. 1,

Fig. 3 is a sectional view on the line 3—3 of Fig. 1,

40 Fig. 4 is a detail plan view of the foot rest, and

Fig. 5 is a detail view of a part of the rocker, showing the same adjusted so that the chair may be used as a rocking chair.

45 Referring more particularly to the drawings, 1 designates the supporting legs of the chair bottom, which legs have rockers 2 and 3 securely attached to their lower terminal ends. The rockers 2 and 3 are of the usual 50 construction, having their lower or under surfaces which engage the floor or surface upon which the chair is placed, arcuate, so as to impart a rocking motion to the chair body (not shown) and they have a foot rest 4 pivotally connected to their forward ends

5. The foot rest 4 extends transversely from the inner side of the rocker 2 to the inner side of the rocker 3, and it has rods 6 loosely connected to its terminal ends, which rods project beyond the inner edge 7 of the foot rest 60 and have their ends 8 curved for engagement with lugs 9, which are carried by the rockers 2 and 3. The foot rest 4 has lugs 10 formed on its opposite ends, which are loosely or 65 rotatably mounted in openings in the sides of the rockers, so as to permit of the pivotal movement of the rocker when the end 8 of the rod 6 is released from engagement with the pin 9.

The rockers 2 and 3 have pivotally connected thereto a brace 11, which brace has legs 12 formed thereupon, and extending at right angles to the brace 11. The legs 12 are connected through the medium of eyelets 13 and hooks 14 to the rods 15, which 75 rods extend rearwardly along the frame of the rocking chair and are slidably seated in the guideways 16, which guideways are supported in spaced relation to the legs 1 of the chair by the rods 17. The rods 15 80 are provided with notches 18 formed in their lower sides, which notches are provided for engagement with the guideways 16 for holding the rods 15 and the brace 11 in various adjusted positions. In the 85 drawings, the brace 11 is shown adjusted so that the legs 12 formed thereon, extend upwardly from the lower edge of the rockers and are out of engagement with the floor upon which the rocker is placed. By moving 90 the brace 11 so that the legs 12 thereof will engage the floor, the angle of the back rest of the chair may be varied, to suit the person sitting in the chair, and also a rigid chair may be provided, in that the engagement between the legs 12 and the floor will 95 prevent the rocking of the chair.

The rockers 2 and 3 have pivotally connected at 20, to their inner sides, wheel supporting arms 21, which arms extend rearwardly parallel with the rockers and have their free ends slidably seated in the guideways 22, which guideways are secured to the inner sides of the rockers and the supporting legs of the chair, in any suitable 100 manner, such as by gluing or by rivets, screws or the like. The pivoted wheel supporting arms 21 have a shaft 23 rotatably journaled therein, substantially equidistant from their terminal ends, which shaft has the 110

rollers 24 mounted thereupon, and adjacent the inner sides of the arms 21, as is clearly shown in Fig. 2 of the drawings. The supporting legs of the chair (not shown) to 5 which the guideways 22 are attached, have catch levers 25 pivotally mounted thereon, as at 26, which catch levers have shoulders 27 formed upon their lower free ends, and handle portions 28 formed upon their upper ends and disposed at right angles to the levers proper for the manipulation of the levers. When the chair is used as a rocker, 10 the catch levers 25 are moved to a position, as is shown in Fig. 5 of the drawings, or so 15 that the shoulders 27 thereon will be out of engagement with the upper edge of the terminal ends of the pivoted wheel supporting arms 21 which ends project through the guideways 22, allowing the arms to 20 move freely within the guideways, and relieve the wheels 24 of the weight of the chair. When the catch levers 25 are moved inwardly, so that the shoulders 27 will engage the upper edge of the projecting ends 25 of the arms 21, the arms 21 will be held against movement within the guideways and the periphery of the wheel 24 will be forced downwardly beyond the lower edge of the rockers 2 and 3, causing the wheels 24 to 30 bear the weight of the chair and the person sitting therein, for converting the chair from a rocker into a wheel chair, as is illustrated in Fig. 1 of the drawings.

The guideways 16 have supporting braces 35 30 formed thereupon and projecting rearwardly from the guideways, which supporting brackets have rigidly connected thereto arcuate bracing arms 31 and 32. The arcuate bracing arms 31 and 32 extend rearwardly of the rear supporting legs 1 of the chair, and inwardly toward each other, having their inner ends rigidly connected at 40 33 to the bracket 34. The bracket 34 has a bearing 35 formed upon its lower rearwardly 45 projecting end, which bearing has slidably and rotatably seated therein the shank 36 of the bifurcated wheel supporting arm 37. The bifurcated wheel supporting arm 37 has a roller or traction wheel 38 rotatably 50 connected between its arms 39 and 40, which wheel is provided for engagement with the floor upon which the chair is placed. The upper end of the shank 36 has a knob or head 41 formed thereupon, which head en- 55 gages the upper end of the bearing 35 and limits the vertical sliding movement of the shank 36, within the bearing. By rotatably and slidably mounting the shank 36 within the bearing 35, the wheel 38 is swivelly supported by the bracket 34, so as to permit 60 of the turning or guiding of the chair while rolling the same about over the floor.

The bearing 35 has pivotally connected thereto a shank lock 42, which shank lock 65 has a recess 43 formed in its upper end for

the reception of the end of the keeper 44. The keeper 44 is pivotally connected at 45 to one corner of the bracket 34, and has its end 46, which is positioned for insertion into the recess 43, slightly reduced.

70

When the improved chair as above described, is used as a rocker, the shank lock 42 is moved so that the shoulder 47 formed thereon will be out of engagement with the head 41 of the shank 36, and the shank will 75 be slidably seated within the bearing 35, to permit of the vertical movement of the wheel support 37 and the wheel 38 upon the rocking motion of the chair.

75

When it is desired to convert the chair 80 from a rocker into a wheel chair, the catch levers 25 are operated so that the shoulders 27 thereon will engage the upper edges of the wheel supporting arms 21, securely holding these arms against vertical movement 85 and causing the peripheries of the wheels 24 to engage the surface of the floor, and consequently raise the rockers from engagement with the floor. The shank lock 42 is then positioned so that the shoulders 47 90 thereof will engage the head 41 of the shank 36, and the keeper 44 is moved upon its pivotal point 45, having its reduced end 46 inserted into the recess 43 in the shank lock 42, to prevent the displacement of the lock. 95 When the shank lock 41 is positioned so that the shoulder 47 will engage the head 42, the shank is held against vertical movement within the bearing 35, but is permitted to rotate therein, and the wheel 38 is held in its 100 lowermost position so that it will engage the floor and provide a swiveled wheel for the guiding of the chair.

100

From the foregoing description taken in connection with the accompanying drawings 105 the advantages of the construction and of the method of operation of the improved invalid chair will be readily apparent to those skilled in the art to which this invention appertains and, while in the foregoing description, the 110 principle of the operation of this invention has been described together with various features of construction, it is to be understood that certain minor features of construction, combination and arrangement of parts may 115 be altered to suit practical conditions provided such alterations are comprehended within the scope of what is claimed.

110

What is claimed is:

In a chair structure, a chair body including supporting legs, rockers carried by said legs, arms pivotally connected to said rockers, supporting wheels carried by said arms, means for holding said arms against pivotal movement for positioning said wheels to relieve said rockers of the weight of said body, a pair of braces connected to certain of said supporting legs, a bracket carried by said braces and having a bearing formed thereon, a shank slidably and rotatably carried by 120 125 130

said bearings, a shank lock pivotally connected to said bearings and adapted to engage the upper end of said shank for holding it against upward movement, and a keeper pivotally carried by said bracket for engagement with said shank lock for holding said shank lock in a locking position.

In testimony whereof I affix my signature in presence of two witnesses.

DANA G. HADLEY.
